FOOD SERVICE CART

Ralph W. Horst, Thornton, Colo., assignor to Wyatt Corporation, Cheyenne, Wyo.

Filed Mar. 27, 1972, Ser. No. 238,741

Term of patent 14 years

Int. Cl. D12—02

U.S. Cl. D12—28

FIG. 1 is a front elevational view of the food service cart showing my new design;

FIG. 2 is a right end elevational view thereof;

FIG. 3 is a top plan view thereof;

FIG. 4 is a rear elevational view thereof; and

FIG. 5 is a left end elevational view thereof.

I claim:

The ornamental design for the food service cart, as shown.
